HOUSECOAT

Henry Farah, New York, N. Y.

Application December 8, 1951, Serial No. 17,657

Term of patent 3½ years

(Cl. D3—26)

To all whom it may concern:

Be it known that I, Henry Farah, a citizen of the United States of America, resident of 50 East Tenth Street, city of New York, county and State of New York, have invented a new, original, and ornamental Design for a Housecoat, of which the following is a specification, reference being had to the accompanying drawing, forming a part thereof.

In the drawing:

Fig. 1 is a front view of a housecoat in undraped position showing my new design;

Fig. 2 is a rear view of Fig. 1;

Fig. 3 is a front view of the housecoat in draped position; and

Fig. 4 is a rear view of Fig. 3.

I claim:

The ornamental design for a housecoat, as shown and described.

HENRY FARAH.
